US00D537080S

(12) **United States Design Patent**
McDonald et al.

(10) **Patent No.:** US D537,080 S
(45) **Date of Patent:** ** Feb. 20, 2007

(54) **DATA CARD**

(75) Inventors: **William Justin McDonald**, McLean, VA (US); **Marc William Mentry**, Glen Allen, VA (US); **Carolyn DeNoia McCarty**, Richmond, VA (US); **Daniel W. McCaskey**, Chapel Hill, NC (US)

(73) Assignee: **Capital One Financial Corporation**

(**) Term: **14 Years**

(21) Appl. No.: **29/209,375**

(22) Filed: **Jul. 14, 2004**

(51) **LOC (8) Cl.** 14-02

(52) **U.S. Cl.** D14/436

(58) **Field of Classification Search** D14/432-38; 361/736-7, 686; D13/182, 184; 40/124.01; 235/487-95, 441-3, 375; 283/900, 904; 257/378-9; 174/52.1; 439/135, 140, 76.1; D19/9, 10

(57) **CLAIM**

The ornamental design for a data card, as shown and described.

DESCRIPTION

FIG. 1 is a front perspective view of a data card showing our new design, on an enlarged scale;

FIG. 2 is a rear elevational view thereof;

FIG. 3 is a front elevational view thereof;

FIG. 4 is a right side elevational view thereof;

FIG. 5 is a left side elevational view thereof;

FIG. 6 is a top elevational view thereof; and,

FIG. 7 is a bottom elevational view thereof.

The broken line drawing in FIG. 2 is for illustrative purposes only and forms no part of the claimed design.
